SALAD IMPLEMENT

Bern E. Wolf and James H. Lee, Los Angeles, Calif., assignors to Prestige Hardware Corporation, Industry, Calif., a corporation of California

Filed Aug. 28, 1961, Ser. No. 66,527

Term of patent 14 years

(Cl. D44—29)

FIG. 1.

FIG. 2.

FIG. 3.

FIG. 4.

FIG. 5.

FIG. 6.

FIG. 7.

FIG. 8.

FIG. 1 is a front elevational view of a salad implement showing our new design, wherein the implement takes the form of a spoon;

FIG. 2 is a side elevational view;

FIG. 3 is a rear elevational view;

FIG. 4 is a transverse, sectional view taken on the broken line 4-4 of FIG. 1;

FIG. 5 is a front elevational view of a salad implement showing our new design, wherein the implement takes the form of a fork;

FIG. 6 is a side elevational view;

FIG. 7 is a rear elevational view; and

FIG. 8 is a transverse, sectional view taken from the broken line 8-8 of FIG. 5.

We claim:

The ornamental design for salad implement, as shown and described.
